FOOD RECEPTACLE FOR CHILDREN

George B. Nathanson, Brookline, Mass.

Application August 11, 1937, Serial No. 158,497

4 Claims. (Cl. 18—59)

This invention relates to a receptacle having its exterior formed of a precious metal, and more particularly to such a receptacle which is adapted to be used by infants or young children.

Heretofore the art has attempted to construct receptacles, such as cups, of precious metals for use by infants or children. However, in this connection, various difficulties have arisen. For example, a precious metal, such as silver, when of thick enough material to withstand being readily dented, makes the receptacle so heavy that it cannot readily be handled by an infant. This likewise necessitates the use of an excessive amount of precious metal which makes the receptacle unduly expensive. Furthermore, a precious metal, such as sterling silver, from which said receptacles are usually made, easily tarnishes particularly when used as a container for infant foods.

An object of this invention is to devise a receptacle of the type described which eliminates each of the above difficulties.

Another object of this invention is to construct such a receptacle which is easily and inexpensively made, and which presents an attractive appearance.

The foregoing and other objects of my invention will be best understood from the following description of an exemplification thereof, reference being had to the accompanying drawing, wherein

Fig. 1 is a cross-sectional view of one embodiment of my invention, showing my novel method of attaching a handle to a receptacle of the type described;

Fig. 2 is a side view of the receptacle shown in Fig. 1;

Fig. 3 is a cross-sectional view taken along line 3—3 of Fig. 1; and

Fig. 4 is a top view of the filling ring used in Fig. 1.

In the embodiment illustrated in Fig. 1 there is shown a cup which consists of an outer shell 12 made of a precious metal, such as sterling silver, and an inner member 13 of a different material such as, for example, a plastic material. The material of which the inner member 13 is made is much lighter in weight than silver, it does not tarnish, and it is acid-proof, non-stainable, and quite hard and resistant to any denting action. As is well known, the term "plastics" is applied in modern terminology to that group of synthetic materials which flows and can be molded to a desired shape by the application of heat and pressure thereto. The term "plastics" is

used in this sense in the specification and in the claims.

In the construction which I have described above, the shell 12 may be made of as thin a material as desired and still present to the user thereof an appearance of a cup or receptacle formed of a precious metal. Thus receptacles such as I have described may be made very inexpensively. However, it is desirable that the shell 12 be made of sufficient thickness so as to serve as a mutual reinforcing element for the inner member 13. The plastic material of which the inner member 13 is made is often of the kind which may fracture, although it is not readily dented. The metal of the shell 12, however, as is well known, is rather ductile and tough so that it does not readily shatter. I have found that the combination of the two materials in the close-fitting contact which I have described produces a unit which is exceptionally resistant both to denting and to fracturing of the constituent members thereof. The composite receptacle described is also of sufficiently light material so that it may be handled easily by an infant. Furthermore, due to the fact that the inner surfaces of the receptacle which come into contact with any foods which may be placed therein are formed of plastic, no tarnishing takes place and the receptacle is easily kept clean.

It is often desirable to make a receptacle having a more or less complex outer surface. In Fig. 2 for example, I show the receptacle having a bulging lower portion 14. In order to secure the advantages of my novel construction, it is, of course, desirable that the entire shell 12 shall closely fit the plastic internal member. This may readily be done in the arrangements which I have illustrated by the use of a filling member 15. This filling member, in the modification which I have illustrated, may take the form of a split ring, as illustrated clearly in Fig. 4. The outer surface of the split ring is shaped so that it snugly fits the interior of the bulging lower portion 14. The inner side of the ring 15 is formed so as to fit snugly the outer surface of the interior member 13. The split ring 15 is formed preferably, but not necessarily, of the same material as the interior member 13. In order to assemble the receptacle, the split ring 15 is first compressed so that the inner ends 16 thereof overlap as shown in Fig. 4. In this way the ring 15 can be decreased in diameter so that it may readily be slipped into the shell 12 until it reaches the enlarged lower portion 14. At that point the ring may be released, whereat its elasticity

will cause it to expand so that the inner ends 16 pass into the position as illustrated in Fig. 3 and completely fill the interior of the enlarged portion 14. If the elasticity of the ring 15 in itself is insufficient to cause such expansion, a tool may readily be inserted to force it into the position as shown in Fig. 3. After the ring 15 is placed in position, as illustrated, the inner member 13 is forced into the shell 12, producing the friction-tight fit between the outer surface of the member 13 and the inner walls of the shell 12, whereby the shell 12 is retained firmly in place on the interior member 13. As indicated, the upper end of the interior member 13 is formed with an enlarged upper edge 17 having a groove formed in its lower side as a continuation of the outer walls of the member 13. The upper edge of the shell 12 fits into the groove and is firmly retained therein due to the tight fit. Thus the completed cup presents a finished and attractive appearance, and is easily assembled. A pattern or letter, such as indicated at 18, may be cut into the shell 12 so as to show the underlying plastic member 13 which may be made in any desired color. By heating the member 13 and exerting a pressure on the interior thereof, plastic material may be extruded through the pattern or letter 18 preferably to such an extent as to lie flush with the outside surface of the member 12, as indicated in Fig. 1. Such an arrangement locks the shell 12 to the inner member 13, and assists in retaining said shell 12 on said member 13.

The extrusion of plastic material through apertures in the shell may be utilized to retain the handle 19 on the composite receptacle, such as shown, for example, in Fig. 1. In this arrangement the shell 12 is provided with two openings 20. The handle 19 is provided with recesses 21 which may be placed in alignment with the openings 20. When the handle 19 is placed in this alignment, the plastic material may be extruded through the openings 20 into the recesses 21 by heating the member 13 and exerting a pressure on the interior thereof. The recesses 21 may be undercut so that the plastic material will form heads 22, interlocking with the handle 19, and thus firmly retaining said handle in place upon the receptacle.

Although in Figs. 1 and 2 a number of features have been disclosed, it is clear that these features need not be used in conjunction but any one or more of them may be used in a particular modification.

This invention is not limited to the particular details of construction as described above, as many equivalents will suggest themselves to those skilled in the art. Also the manner in which the upper end of the shell is retained on the receptacle may be subjected to a wide variety of different treatments. Other modifications and equivalents will readily present themselves. It is accordingly desired that the appended claims be given a broad interpretation commensurate with the scope of the invention within the art.

What is claimed is:

1. A composite receptacle comprising an outer shell of a relatively thin precious metal, an inner receptacle member of plastic, said outer shell being provided with an annular enlargement, and a split ring of plastic fitting snugly within said enlargement having its interior surface formed to lie in the plane of the rest of the interior surface of said shell, producing a regular interior surface into which said inner receptacle fits uniformly and tightly.
2. A composite receptacle comprising an outer shell of a relatively thin precious metal, an inner receptacle member of plastic material, the inner walls of said outer shell firmly engaging the outer walls of said inner receptacle member, said shell being perforated, said plastic material extending through said perforation to form a handle-attaching projection, and a handle secured to said projection.
3. The method of producing a composite receptacle which comprises perforating an outer shell of a relatively thin metal, supporting an external member adjacent the perforation, said external member having an aperture thus held in alignment with said perforation, placing a plastic material which can be molded under the application of heat and pressure thereto within said shell, heating said material, and exerting a pressure upon it from the interior of said shell to extrude said material through the perforation in said shell into said aperture to retain said external member on said shell.
4. A composite receptacle comprising an outer shell of a relatively thin metal, an inner receptacle member of plastic material, the inner walls of said outer shell firmly engaging the outer walls of said inner receptacle member, said shell being perforated, said plastic material extending through said perforation to form an external projection for attaching an additional member, and an additional member attached thereto.

GEORGE B. NATHANSON.
